Herman L. Wicksen

UNITED STATES PATENT OFFICE

HJALMAR ERIKSSON, OF SKOLDINGE, SWEDEN

MACHINE FOR MIXING TWO OR MORE SUBSTANCES WITH EACH OTHER

Application filed November 9, 1927, Serial No. 232,163, and in Sweden June 16, 1927.

This invention relates to a machine for mixing two or more substances with each other, for instance ore concentrate or the like, with coal or coke breeze for the purpose of 5 either rendering the mixture fit for the sintering process or for turning it into pieces or the like.

The mixing devices used hitherto for preparing the respective substances for the 10 sintering procedure suffer from the drawback that the mixing is not thorough enough. It occurs frequently that the clods or clogs contained in the raw material or materials, for instance in iron ore concentrates, leave 15 the mixing device in the same state in which they have been introduced into it. Thorough mixing is, however, very important, and decisive for the result, especially for the sintering procedure, if this is to proceed 20 properly and uniformly. The object of the present machine is to bring about this result, and is attained by means of a drum, preferably a vertical drum, which receives the substances to be mixed and through 25 which extend rods arranged crosswise with respect to, and in several distances from each other. An axle arranged in said drum is provided with arms located in the spaces between the superposed rods. These latter 30 which can be moyed together with the drum, and the arms which can be stationary in that they are attached to said axle co-operate and effect a very thorough and intimate mixing of the respective substances. Clods or clogs 35 or the like are completely reduced to very fine particles, the more, as it is possible to work the substances in the machine as long as desired, in that the drum can be rotated as long as required to attain the result aimed 40 at, which is not possible with the existing uninterrupted working machines, in which the materials remain in the drum a period of time of predetermined length.

The invention is illustrated diagrammatically and by way of example on the accompanying drawing on which Figure 1 is a vertical axial section through a constructional form of a machine designed according to this invention, and Figure 2 is a plan of the 50 same.

On the drawing, 1 denotes a vertical cylindrical drum carried by means of a ball bearing comprising a bevel-ring 2 secured to the drum, balls 3 and a race-ring 5 which is carried by vertical standards 4 of U-iron by the 55 intermediary of brackets 4^a. The bevel-ring 2 meshes with a bevel-wheel 6 affixed to a short horizontal shaft 7 provided at its outer end with a pulley 8. The bearing 7^a supporting these members is carried by one pair of 60 the standards 4. It is obvious that the drum 1 can be rotated as long as desired.

9 denotes a ring affixed to the drum 1 above the gear members 2 and 6 and protecting them from being covered with particles of the 65 materials thrown into the drum.

The pairs of standards 4 extend upwardly from a base 10. The position of the drum with respect to this base is such that its lower edge is nearly in contact with the surface of 70 the same. Below the drum a discharge opening 11 is provided in the top plate of the base 10, and the free sectional area of this opening can be varied by means of two slides 12.

The standards 4 are connected with each 75 other at their upper ends by two girders 16 connected with each other by a member 17 serving as upper hold for a vertical rod 13 of square section, the lower end of which is supported on the base 10. This rod carries 80 arm-crosses 14, of which there may be only two, as in the drawing, or more, corresponding to the size of the machine. The arms co-operate with pairs of rods 15 supported in the wall of the drum 1 and arranged in 85 pairs which cross one another and are, besides, superposed. Each arm-cross is located between two upper pairs of rods 15 and two lower pairs of these rods. I wish it, however, to be understood that the drawing shows 90 merely one example of the several possibilities regarding the arrangement and the number of the rods 15, there being only the one presupposition that the centre of the drum remains free in order to provide for the space 95 necessary for the rod 13.

The substances to be treated and mixed are introduced into the drum from above, and their amount is so chosen that also the uppermost pair of rods 15 is covered with them. 100

- The substances are mixed with each other by turning the drum with its rods 15 by means of the gearing 8, 7, 6, 2, and the turning is continued until a perfectly satisfying mixture has been produced which can be ascertained by specimens taken through the opening 11. The finished mixture is withdrawn through this opening by and by, and a corresponding amount of fresh substances to be 10 mixed is replenished into the drum from above. The operation can, thus, be carried through continuously, but every charge can be worked as long as desired until the quality of the product is that desired.
- 15 I wish it also to be understood that the machine may be reversed in this way that the drum 1 with its transverse rods 15 is stationary, and the vertical rod 13 is replaced by a vertical shaft also provided with arm- 20 crosses 14. It is, furthermore, possible to combine the two constructional forms that is to say, the drum can be rotatory and the arm-crosses as well, and means may be provided for rotating the drum and the arm- 25 crosses in opposite directions.

I claim:

1. A mixing machine, comprising, in combination, a revolute drum, sets of rods traversing said drum at some distance from its 30 longitudinal axis and being affixed to the wall of said drum, sets of radially extending rods located in planes between the planes of said first-mentioned rods, a centrally arranged stationary holder for said radially 35 extending rods, and means for causing said drum to revolve.
  2. A mixing machine, comprising, in combination, a revolute drum, sets of rods traversing said drum in different horizontal 40 planes and at some distance from its vertical axis, said rods being affixed to the wall of said drum, sets of radially extending rods located in planes between the planes of said first-mentioned rods, a centrally arranged 45 stationary holder for said radially extending rods, means for causing said drum to revolve, and a stationary bottom for said drum and having an eccentrically disposed discharging opening.
- 50 In testimony whereof I affix my signature.

HJALMAR ERIKSSON.
